COMBINED WASHING MACHINE AND EXTRACTOR

Frank M. Risch, University City, Mo.

Application April 14, 1930, Serial No. 443,953

3 Claims. (Cl. 68—38)

This invention relates to cleaners, and has more particular reference to a machine that can be used for dry-cleaning clothes and other fabric. The principle purpose of the present invention is to provide a machine of this character that can be employed for the purpose of extracting the cleaning fluid from the cleaned clothes as well as for cleaning the clothes. Another object of the present invention is the provision of a cleaner that will fulfill this two-fold purpose without involving the use of alternative mechanisms for the respective purposes. Another object of the present invention is to provide a two-fold purpose cleaner that may be adapted from one purpose to the other by merely changing its position. A further object is to provide a small portable cleaner or extractor that will be simple in construction and operation and that can be easily operated by hand. Other objects, advantages, and desirable features of the invention will appear in the course of the following description of an illustrative embodiment of the spirit of the invention.

In the accompanying drawings forming part of this specification, in which like numbers of reference denote like parts wherever they occur,

Figure 1 is a plan view of the cleaner;

Figure 2 is a vertical longitudinal central sectional view of the same, showing the door open;

Figure 3 is a front elevation of the cleaner;

Figure 4 is a transverse sectional view of the same, taken on the line 4—4 in Figure 2, but with the door closed; and

Figure 5 is a longitudinal sectional view taken on a plane, approximately, on the line 5—5 in Figure 3, so as to show the interior parts in elevation, and also showing the device turned to stand on its rear end so as to be in its extracting position.

The device comprises a vessel or tank 1, preferably constructed of sheet metal, and having a bottom 2, side walls 3 and 4, a rear wall 5, a front wall 6 and a top wall 7. The front wall 6 and the top wall 7 terminate at 8 and 9, respectively, about half way short of the line of intersection of their planes, and the side walls 3 and 4 also terminate short of the said line of intersection along obliquely disposed edges 10 that co-operate with the edges 8 and 9 to form a rectangular inclined opening 11 in the tank 1. The front edge 8 and the side edges 10 of the opening 11 are preferably bent inwardly and then outwardly to form substantially V-shaped channels 12 to receive the inwardly presented flanges 13 formed on the front and lateral edges of a door 14 adapted to close

the opening 11. The rear edge 15 of the door is hinged at 16 to the front edge 9 of the top wall 7. A flange 17 projects inwardly from the rear edge 15 of the door at an angle such that it will be parallel to and abut against the underside of the top wall 7 when the door is closed.

The flanges 13 and 17 stiffen the sheet metal door 14 and also co-operate with the channels 12 and top wall 7, respectively, to make a tighter and more effective closure for the opening 11. A semi-cylindrical interior false bottom 18 extends over the bottom wall 2 and the lower portions of the side walls 3, and the longitudinal edges of the bottom 18 are soldered, welded, or otherwise suitably secured to the inner sides of the walls 3 so the upper portions of the latter form an uninterrupted rising continuation of the lateral portions of the bottom 18.

The holder for the clothes or other work is preferably in the form of cylindrical sheet metal container 19 having a front end wall 20, a rear end wall 21, and a cylindrical wall 22. Suitable perforations 23 are provided in the walls 21 and 22.

The wall 22 contains an opening 24, which is closed by a perforated door 25, secured to one edge 26 of the opening 24 by hinges 27, and adapted to be secured in closed position by a pin 28, inserted for the purpose through tubes or sockets 29 and 30 formed on the other edge 31 of the opening and on the corresponding edge 32 of the door, respectively, so that they will be in alignment when the door 25 is closed. The inner side of the wall 22 of the container 19 bears ribs 33 that lift and tumble the clothes or work in the cleaning liquid in the cylinder or tumbler 19 when the latter is rotated with its axis horizontal. Each of the ribs 33 is slotted or notched transversely on its under side at intervals along its length as at 34 to permit the passage under the rib of cleaning liquid from one to the other of the sides of the rib. The heads or ends 26 and 21 have secured thereto on their outer sides respective centrally disposed bosses 35, in which are rigidly secured respective trunnions 36 and 37. The rear trunnion 37 is journaled in a bearing 38 in a bracket 39 suitably attached in a leaf-proof manner to the inner side of the rear wall 5, as by means of bolts 40 whose heads are soldered or welded to the inner side of the wall 5.

The front trunnion 36 is journaled in a bearing in a plate 41, rigidly secured to the inner side of the front wall 6, and extends exteriorly from said bearing through an aligned opening in the front wall. The outer end of said trunnion bears a spur pinion 42 in such manner that the

trunnion 36 and pinion 42 rotate as if they were integral, as best shown in Figure 2. A plate 43 is secured over the outer side of the front wall 6 by means of bolts 44 that pass through washers 5 45 interposed between the wall 6 and the plate 43 to maintain them suitably spaced apart. A spur gear 46 is arranged to turn between the wall 6 and plate 43 and to mesh with the pinion 42, as best shown in Figures 1, 3, and 5. A spur gear 46 is keyed or otherwise affixed to a stub shaft 47 so as to rotate therewith. The shaft 47 is journalized in a bearing in the plate 43, and the outer end of said shaft projects beyond said bearing and has affixed thereto, so as to rotate therewith, a crank 48.

The construction of the device having been fully described, its mode of operation will be readily understood. The tank 1 is turned so that its rear wall 5 forms the bottom, as shown in Figure 5, and the door 14 is opened and cleaning liquid poured into the tank through the opening 11 until the level 49 of the liquid nearly reaches the rear head 21, now the bottom, of the now upright cylinder 19. The door 25 of the cylinder 25 19 is opened, and the clothes or articles to be cleaned are introduced through the opening 24 into the tumbler 19, after which the door is closed, and secured by passing the pin 28 into the sockets or sleeves 29 and 30. The tank is then turned on the common edge 50 of the rear wall 5 and the bottom 2 until it rests on its bottom 2, as shown in Figures 1, 2, 3, and 4. The turning of the tank is accompanied, of course, by a shifting of the body of liquid therein, which enters the tumbler 19 through the perforations 23 to the proper level found to be best for the purpose. The tumbler 19 is then rotated by turning the crank 48, preferably first in one direction and then in the opposite direction, and so on, thereby imparting an alternating rotative velocity to the tumbler, which velocity is greater than that of the hand crank 48 by reason of the velocity step-up obtained through the pinion 42 and gear 46.

When the clothes have been cleaned by this operation, the tumbler is allowed to come to rest, and the tank is turned back on the edge 50 so that it again rests on its rear wall 5, as shown in Figure 5. The tumbler 19 is then rotated at a high velocity in one direction, the cleaning liquid draining from the clothes and emerging from the tumbler 19 through the perforations 23 by gravity.

The high velocity of the basket 19 causes it to function also as a centrifugal extractor that very thoroughly removes nearly all of the cleaning fluid from the clothes. Merely allowing the cleaning fluid to drain from the clothes often leaves streaks or spots of discoloration due to uneven draining, but the centrifugal action removes the cleaning fluid so thoroughly that streaks and discolorations are prevented. It will be quite apparent that the concave false bottom 18 more closely follows the cylindrical wall 22 of the drum 19 than does the bottom 2 and thereby reduces the volume of liquid that is necessary to raise the liquid to a predetermined level in the tumbler 19 when the axis of the latter is horizontal. It will also be observed that the work holder 18 is positioned closer to the concave bottom 18 than to the lateral rear wall 21, whereby, when the vessel 1 stands on its bottom and is filled with a cleaning liquid to a predetermined level so as to immerse partly, at least, said holder, said liquid will drain 75 from said holder toward said lateral wall when the

vessel is turned to lie on said lateral rear wall 21. It will be observed further that, the greater the distance of the top wall 7 from the bottom wall 2, the smaller need be the distance between the wall 5 and the rear end 21 of the tumbler 19 without liability of causing the liquid to rise into the tumbler 19 when it is in the extracting position shown in Figure 5. Otherwise stated, the interior configuration of the vessel 1 is such that, when the vessel 1 is positioned so that the axis of rotation is substantially vertical, the level of a predetermined volume of liquid in the vessel 1 will fall below the interior of the tumbler 19, and, when the vessel is positioned so that the axis of rotation of said tumbler is substantially horizontal, the cleaning liquid will rise to enter said tumbler. When the cleaning and extracting operations have been completed, the doors 14 and 25 are opened, and the articles or work removed, after which the foregoing cycle of operations may be repeated to clean the next batch of work.

Having thus fully described this invention, I hereby reserve the benefit of all such changes in form, arrangement, order, or use of parts as will fall within the scope of the following claims, as it is evident that many changes may be made therein without departing from the spirit of this invention or the scope of the following claims.

I claim:

1. In a washing machine, a substantially polyhedral box, an operating spindle extending through one side of the box, and a work container borne by said spindle in juxtaposition to said side and an adjacent side and remote from the two sides opposite the two first-mentioned sides, the 30 said box having a work-introducing opening intervening between the first-mentioned side and the side opposite the second-mentioned side, whereby when said box is positioned to rest on one of said adjacent sides the container will be immersed 35 in a cleaning liquid in the box and when the box is placed on one of said remote sides the container will be above the normal level of said liquid.

2. In a washing machine, a substantially polyhedral box, a rotatable work container, means 45 for rotatably supporting said work container in said box at a fixed location in juxtaposition to two adjacent sides and remote from the two sides opposite the two adjacent sides, there being an oblique side formed intermediate one of said adjacent sides and one of said opposite sides, said oblique side including an opening for the passage of work into or out of the box, and a movable cover for the opening, whereby when said box is positioned to rest on one of said adjacent sides the 50 container will be immersed in a cleaning liquid in the box and when the box is placed on one of said remote sides the container will be above the normal level of said liquid.

3. A washing machine of the class described including a box having four sides which are at right angles to each other and having a fifth side which is oblique, a closing means adapted to fit said oblique side, a rotatable work container, means for supporting the said work container in the 65 said box at a fixed location in juxtaposition to two adjacent sides, in close proximity to said oblique side, and remote from the two sides opposite the said two adjacent sides, whereby when said box is positioned to rest on one of said adjacent sides the container will be immersed in a 70 cleaning liquid in the box and when the box is placed on one of said remote sides the container will be above the normal level of said liquid.
